(57) **CLAIM**

The ornamental design for an aircraft galley oven door, as shown and described.

DESCRIPTION

FIG. 1 is a front perspective view of an aircraft galley oven door, showing my new design, the broken line showing is for illustrative purposes only, and forms no part of the claimed design;

FIG. 2 is a top plan view thereof;

FIG. 3 is a front view thereof;

FIG. 4 is a bottom view thereof;

FIG. 5 is a left hand view thereof;

FIG. 6 is a right hand elevational view thereof; and,

FIG. 7 is a perspective view of a second embodiment thereof.
